Primary Examiner — Kendra Leslie Hamilton(74) *Attorney, Agent, or Firm* — HYIP(57) **CLAIM**

The ornamental design for a dog harness, as show and described.

DESCRIPTION

FIG. 1 is a top, front, left perspective view of a dog harness, showing our new design in a first configuration for use;

FIG. 2 is a top, rear, right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, left perspective view of the dog harness of FIG. 1, in an alternate configuration for clarity of disclosure;

FIG. 10 is a top, rear, right perspective view thereof;

FIG. 11 is an enlarged view of detail "11" identified in FIG. 1; and,

FIG. 12 is an enlarged view of detail "12" identified in FIG. 1.

1 Claim, 12 Drawing Sheets
